METHOD OF PROCESSING VISCOUS HYDROCARBON OILS

Filed March 21, 1930

UNITED STATES PATENT OFFICE

1,935,693

METHOD OF PROCESSING VISCOSUS
HYDROCARBON OILS

John C. Black, Beverly Hills, Calif.

Application March 21, 1930. Serial No. 437,892

6 Claims. (Cl. 196—51)

This invention relates to a method of processing hydrocarbon oils such as crude petroleum oils, petroleum oil residuums, fuel oil and the like, for the production of high boiling distillates 5 and a marketable residuum suitable for fuel oil and other like purposes.

By well-known methods, high boiling distillates such as gas oil and lubricating oil stocks are obtained by distillation of crude petroleum oil, or petroleum oil residuums in which a residuum may be obtained which is too viscous for a marketable fuel oil without the addition of a relatively large amount of a solvent petroleum oil distillate or other solvents, to obtain a sufficiently fluid mixture to meet the viscosity required for the various grades of fuel oil.

The petroleum oil distillates usually employed to reduce the viscosity of viscous petroleum oil residuums are light gas oil stocks which may or 20 may not contain lamp oil or other distillates which are sufficiently fluid and of the least value for the production of refined marketable products. It is therefore a difficult problem for refineries to obtain a sufficient amount of an inexpensive solvent distillate to reduce the viscosity 25 of the large amounts of the viscous residuums obtained in distillation operations to obtain a marketable product, since gas oil stocks or other high boiling distillates usually employed have become 30 more valuable as a cracking stock for the production of synthetic gasoline.

In distilling a lubricating distillate or a gas oil fraction at normal atmospheric pressure, from crude petroleum or petroleum residues, the 35 oil is heated in tubular stills or shell type stills to high temperatures to remove the high boiling distillates desired.

In operating a tubular still for this purpose, temperatures as high as 700 to 800 degrees F. or 40 somewhat higher may be employed and even as high as 850 degrees F. may be employed if a large yield of distillate is required. This high temperature is necessary to supply the heat of vaporization to permit the desired fractions to 45 distill when the oil is discharged into the evaporator, the temperature being so regulated in the heating step that sufficient heat is provided in the body of oil to furnish the heat of vaporization, with the result that the residues are very 50 materially cooled from the temperature at which the oil entered the evaporator. This cooling effect may be as much as 50 degrees more or less, depending upon the amount distilled off in the form of a distillate. The residue derived from 55 this operation, if cooled down immediately by

heat exchangers or coolers, would be found to be of a viscous nature and usually unsuitable for fuel purposes, due to its high viscosity. This is especially so where a large percentage of distillate has been taken off. The residue may even 60 partake of the nature of an asphalt where a naphthenic base oil has been processed; or a heavy waxy residue when a paraffin base oil has been used, the latter also having a high cold test which makes it further unsuitable for fuel oil 65 requirements.

It is well known in the art that heavy or viscous petroleum oils may be heated in a cracking apparatus to a temperature sufficient to crack the hydrocarbons, then distilling off the lighter fractions 70 and leaving a residue whose viscosity is lower than the original oil. The sediment however, is high where cracking is resorted to and often makes the oil unsuitable for sale without admixture of other low sediment oil to average down 75 the sediment and free carbon.

Now I have discovered that if the lubricating distillate or gas oil fraction is distilled in the evaporator from the original charging stock and the residue still retaining its heat after evaporation is permitted to accumulate in the bottom of the evaporator, the viscosity of the residue will be materially reduced but will have a high sediment and free carbon content which render it 80 unsuitable for sale. This is true when the evaporator is working under substantially atmospheric pressure.

I have also discovered that if a superatmospheric pressure is maintained on the evaporator the sediment and free carbon is greatly reduced 90 but this again has a serious drawback in the fact that if a high pressure is maintained on the evaporator sufficient to prevent carbon formation in the residue, then more heat has to be applied to the charging stock and its temperature 95 raised in order to evaporate the desired lubricating distillates or gas oil fractions because the pressure raises their boiling point. Now this increased temperature in turn tends to increase the carbonization of the oil, principally the heavy 100 residue, with the result that more sediment and free carbon are produced, rendering the residue unsalable or at least lessening its value.

However, it may be found desirable to carry a certain amount of pressure on the evaporator 105 to permit carrying a higher temperature on the ingoing oil and at the same time to obtain the desired yield of distillates in order to furnish sufficient heat to the residue for its subsequent decomposition, but this pressure is only nominal 110

compared to the pressure employed in the decomposition step of the residue to be later described.

To overcome these difficulties I have devised a process wherein the distillates are removed at the optimum temperature for their removal at the pressure employed on the evaporator and at such a temperature that the residue will have sufficient heat to bring about the desired decomposition or molecular rearrangement in the subsequent digestion and pressure step and wherein the residue is immediately removed from the evaporator by a pump and discharged into a pressure digester or reservoir preferably insulated, so the oil will not lose its heat; and the digester reservoir is made with a capacity such that it will hold the oil in transit through it for a suitable length of time so that a conversion of the hydrocarbons will take place and a residue will result which has much greater fluidity than the original oil entering the reservoir. Furthermore, the process employs a comparatively high pressure on the digester or reservoir to prevent any considerable evaporation of the lower boiling fractions generated by the decomposition of the high boiling viscous hydrocarbons, which comprise the original residue entering the digester or reservoir, and I have discovered that in preventing this evaporation by impressing a pressure upon the oil in the digester or reservoir by the charging pump of such a magnitude that it will exceed the vapor pressure of the lower boiling fractions generated by the decomposition above referred to, the sediment and free carbon residue will be negligible and will meet fuel oil specifications without admixture with other low sediment fuel or lighter distillates to make it salable.

The pump pressure and the pressure on the digester or reservoir may be as high as 500 lbs. per sq. in. or more, depending upon the oil treated, some oils requiring as high as 700 lbs. or more and in some cases a pressure less than 500 lbs. may be sufficient.

The time in which the oil is retained in the pressure reservoir also depends upon the character of the oil and may be as long as an hour or more. In some instances a shorter time may suffice to bring about the desired decomposition of the viscous residue. I have also discovered that coincident with the increased fluidity of the resulting residue that the cold test has been lowered very materially, in some cases as much as 30 degrees F.

As an example of the application of my invention for obtaining a high boiling distillate or cracking stock for the production of synthetic gasoline and a marketable residuum suitable as a fuel oil from fuel oil obtained in general refinery practice, a naphthenic base fuel oil having a gravity of 17.5 degrees A. P. I. and a viscosity of approximately 85 seconds at 122 degrees F. (Saybolt Furol viscosimeter) was heated to a temperature of 780° F. under a pressure of approximately 90 pounds gauge, and then subjected to a distillation operation at a pressure of approximately 10 pounds gauge and 40 per cent of a high boiling distillate or gas oil stock was distilled off, leaving a heavy asphaltic residuum which was semi-solid at ordinary temperature and not sufficiently fluid at 122 degrees F. to obtain a Saybolt Furol viscosity determination.

This heavy asphaltic residuum coming from the distillation operation, and while retaining its heat from the distillation operation, was then subjected to digestion at an average temperature

of 730 degrees F. for 60 minutes and under a pressure of over 700 lbs. gauge and after cooling, the viscosity was reduced to 123 seconds at 122 degrees F. (Saybolt Furol viscosimeter).

One of the objects of this invention is to provide a process wherein a residue from a distillation process is rendered more fluid. 80

Another object of the invention is to produce a residue of low sediment and substantially free from uncombined carbon content. 85

Another object is to produce a final residue of lower cold test than the original residue.

Another object of the invention is to reduce the viscosity of viscous petroleum residua by a molecular rearrangement to produce a marketable fuel oil without the use of solvent petroleum oil distillates. 90

Another object of the invention is to utilize the retained heat of the petroleum oil residuum coming from a distillation operation to reduce the viscosity of the petroleum oil residuum. 95

Another object of the invention is to obtain a maximum yield of high boiling distillates from a petroleum oil and a marketable residuum suitable as a fuel oil. 100

Another object of the invention is to provide an apparatus to carry out the process in a continuous manner.

From the foregoing description of the process it will be seen that a continuous process is described that has many features of novelty and the apparatus later to be described shows the equipment necessary to carry on the process. 105

The drawing represents a diagrammatic view of the apparatus in which the parts are in vertical section. 110

In the drawing, 1 represents a tank for holding the oil to be processed, such as an asphaltic or mixed base crude petroleum oil, from which the lower boiling hydrocarbons may or may not have been separated by a prior distillation operation. 115

Tank 1 is filled with the petroleum oil to be processed by opening valve 80 in the pipe 71. From tank 1 the oil flows through pipe 4 and 120 into the suction side of pump 2 which discharges the same in a regulated stream flow through pipe 5, heat exchanger 3, pipe 10, heat exchanger 14, pipe 18, heat exchanger 61, pipe 64 and heating coil 67, under a pressure sufficient to prevent any substantial vaporization. Heating coil 67 is stationed in the top of furnace 68. The furnace 68 is provided with a burner 65 stationed in the lower section of the furnace. The burner 65 is connected to a source of fuel supply not 130 shown and regulated so as to supply a sufficient amount of heat to heating coil 67, to heat the preheated oil passing through the coil 67 to a temperature ranging from 700 to 800 degrees F. or more, this temperature depending upon the 135 boiling points of the distillates to be separated from the petroleum oil stock and the heat required in the residue to bring about the decomposition or molecular rearrangement desired without extensive cracking and formation of 140 low boiling hydrocarbons. In case it is desired to separate a relatively low boiling distillate only, a lower temperature than 700 degrees F. may be employed. The oil passing through the heating coil 67 is maintained at a pressure ranging from 145 25 to 100 pounds gauge or higher, depending on the volatility of the oil and temperature to which it is heated and the frictional resistance of the coil and connections. From heating coil 67 the heated oil passes through pipe 66 containing 150

5 a pressure regulating valve 53. Pipe 66, ending in spray pipe 49, discharges the heated oil into fractionating tower 46 wherein the lower boiling oils or naphtha stock together with a higher boiling distillate are vaporized and separated from the residual products. The fractionating tower 46 is provided with boiling decks 48 in the lower section and a separator plate 47 located just above the boiling decks 48. The fractionating tower 46 is also provided with boiling decks 88 situated above the separator plate 47 and a spray pipe 45 for the introduction of a wash oil to condense and separate the higher boiling distillate from the vaporized lower boiling oils or naphtha stock.

10 The vaporized oil passes up through boiling decks 48 then through the vapor outlet in separator plate 47 and into the top section of fractionating tower 46, whereby the vaporized oil is separated from the residual products. The vaporized oils passing up through boiling decks 88 are fractionated and the higher boiling fraction condensed by the continuous introduction of a cooler wash oil introduced through spray pipe 45. The lower boiling vaporized naphtha fraction, (if present in the oil being processed) separated from the higher boiling oils, passes out of fractionating tower 46 at the top through pipe 44, valve 44' and into condenser coil 43 which is 15 stationed in condenser box 42, wherein the major portion of the naphtha stock is condensed and passes through pipe 40 into look box 39. In look box 39 the condensed naphtha stock is separated from the gaseous product and passes through pipe 38 into receiving tank 37. From tank 37 the naphtha stock may be conducted to a storage not shown through pipe 69 controlled by valve 70, and purified by methods known in the art. The gaseous products separated from the naphtha stock in look box 39 pass through pipe 41 20 into pipe 87. Pipe 87 leads to an absorber not shown whereby the retained naphtha stock is separated from the non-condensable gaseous products and returned to tank 37 or to other storage not shown.

25 The condensed higher boiling distillate and wash oil stock which collects above the separator plate 47 passes out of the fractionating tower 46 through pipe 50 and into the suction side of pump 63, which discharges the same through pipe 62, heat exchanger 61, pipe 60, cooler 59, pipe 58 and into receiving tank 57.

30 A portion of the cooled higher boiling distillate which collects in tank 57 is continuously returned to fractionating tower 46 passing from tank 57 through pipe 56 into the suction side of pump 55. Pump 55 discharges this distillate through pipe 54 which terminates in spray pipe 45 in the top of fractionating tower 46. The excess quantity 35 of high boiling distillate which collects in tank 57 is continuously or intermittently conducted to a storage not shown by opening valve 90 in the pipe 90' and may thereafter be cracked for the production of gasoline stock or utilized for the manufacture of other petroleum oil products known in the art.

35 The residuum or residual oil product at a temperature of approximately 700 to 800 degrees F. or more collects in the bottom of fractionating tower 46 and immediately and continuously passes out of tower 46 through pipe 52 into the suction side of pump 51. Pump 51 continuously discharges the hot residuum through pipe 22 which ends in a spray pipe 23 inside of digester 19 near the top. The digester 19 is maintained

under a pressure sufficient to prevent any substantial vaporization therein, which may be as high as 700 pounds gauge or more, depending upon the temperature of the residuum, the time of digestion and the extent of decomposition.

40 By a regulated closing of valve 44, fractionating tower 46 may be maintained under any pressure so as to regulate the percentage separation of lower boiling oils from the higher boiling fraction and whereby the residual oil passing to the digester 19 may be maintained at temperatures sufficiently high to obtain the required decomposition. The pressures maintained on pipe 22 and digester 19 are indicated by pressure gauges 20 and 21.

45 It will be noted that in my preferred form of apparatus that the reaction reservoir or digester 19 is a vertical cylinder with the inlet from the charging pump 51 at the top ending in a spray pipe 23, so that as the oil is withdrawn from the bottom outlet of the digester into pipe 15 controlled by pressure regulating and discharge valve 17, there is a gradual flow downward of the oil in the reservoir or digester 19, the latter being kept full or at the height of the inlet (spray pipe 23) and due to the fact that the inlet oil is hotter than the oil withdrawn from the bottom outlet, there is no tendency to intermix due to convection currents and the oil remains in the reservoir or digester 19 for the required reaction time.

50 The digester 19 is preferably covered with an insulating coating such as cork, magnesia or other insulating material 19' to prevent loss of heat from radiation. The digester 19 is also provided with the pressure regulating and discharge valve 25 connected to a liquid level control device as indicated on the drawing. The pressure regulating and discharge valve 25 may be set for any pressure desired, and when that pressure is exceeded will discharge the fluid content from the top of digester 19 into pipe 24.

55 From pipe 24 the fluid content, which may be hot residuum or hydrocarbon gases, pass into fractionating tower 26. From the digester 19 the processed residuum passes through pressure regulating and discharge valve 17, pipe 15, heat exchanger 14, pipe 16 and then into fractionating tower 26. Fractionating tower 26 is provided with boiling decks 27 and evaporating trays 28. In fractionating tower 26 the naphtha stock and gaseous products produced in the digesting operation of the residuum together with the naphtha stock and gaseous products coming through pipe 24, are separated from the processed residuum. The separated naphtha stock and gaseous products pass out of fractionating tower 26 through pipe 30, cooling coil 31, which is stationed in cooling box 36, pipe 32 and into look box 33 wherein the non-condensable gases separate from the naphtha stock and pass out of the look box 33 at the top into pipe 85. From pipe 85 the gaseous products pass into pipe 86 which is connected to an absorber not shown wherein the retained naphtha stock may be recovered. From look box 33 the condensed naphtha stock passes through pipe 34 and is collected in tank 35. By means of pipe 83 controlled by valve 84, the collected naphtha stock may be conducted to a storage not shown.

60 From fractionating tower 26 the processed residuum continuously passes into pipe 13 and then into the suction side of pump 12, the flow being controlled by operation of valve 29. The pump 12 discharges the hot processed residuum

through pipe 11, heat exchanger 3, pipe 6, cooler 7, pipe 8 and then into tank 9. The hot processed residuum passing through heat exchanger 3 and cooler 7 is cooled to the required degree. From tank 9 the processed residuum may be transported to other storage not shown through pipe 81 controlled by valve 82 and may thereafter be utilized as a fuel oil or other marketable residual oil product known in the art.

10 By the clause "sufficient to prevent substantial vaporization", as used in the specification and claims of this application, it is meant that approximately 10 per cent or less of the residual oil being processed is in a vapor form, and in-
15 sufficient to cause carbonization.

While the process herein described is well adapted for carrying out the objects of the invention, it is to be understood that various modifications and changes may be made without de-
20 parting from the spirit of the invention, and the invention includes all such modifications and changes as come within the scope of the appended claims.

What I claim is:

25 1. A method of processing petroleum oils, comprising, separately separating by low pressure distillation and fractionation a lower boiling distillate, a higher boiling distillate, and a viscous petroleum oil residuum from a petroleum oil, at temperatures substantially not less than 700° F., continuously passing the heated petroleum residuum without further heating, and at a temperature of its retained heat from the low pressure distillation operation, through an enlarged digesting zone maintained at an increased pressure of about 500 pounds per square inch, sufficient to prevent substantial vaporization therein, and at a temperature of not less than about 700° F., regulating the time of flow through the digesting zone sufficient to produce a molecular rearrangement of the heated petroleum residuum, and producing a fuel oil of lowered viscosity.

40 2. A method of processing petroleum oils, comprising, separately separating by low pressure distillation and fractionation a distillate and a viscous petroleum oil residuum from a primary residual petroleum oil, at temperatures substantially not less than 700° F., continuously passing the heated viscous petroleum oil residuum, without further heating and at a temperature of its retained heat from the low pressure distillation operation, through an enlarged digesting zone maintained at an increased pressure of about 500 pounds per square inch, sufficient to prevent substantial vaporization therein, and at a temperature of not less than about 700° F., regulating the time of flow of the heated viscous petroleum oil residuum through the digesting zone sufficient to produce a molecular rearrangement of the heated viscous petroleum residuum, and producing a fuel oil of lowered viscosity.

45 3. That step in the method of processing viscous petroleum oil residuum to render the same less viscous, comprising, passing a heated viscous petroleum oil residuum, from which distillates

have been separated by distillation and fractionation of a petroleum oil, without further heating and at the temperature of its retained heat from the distillation operation, through an enlarged digesting zone maintained at an increased pressure of about 500 pounds per square inch, sufficient to prevent substantial vaporization therein, and at a temperature of not less than about 700° F., regulating the time of flow through the digesting zone sufficient to produce a molecular rearrangement of the heated viscous petroleum oil residuum, and producing a fuel oil of lowered viscosity.

50 4. A method of reducing the viscosity of viscous petroleum oil residuum, comprising, subjecting heated viscous petroleum oil residuum coming from a low pressure distillation and fractionation operation, at a temperature of not less than about 700° F., to an increased pressure of about 500 pounds per square inch, produced by mechanical means, sufficient to substantially prevent further vaporization thereof, and then without further heating passing the heated residuum at said pressure and said temperature through an enlarged digesting zone, regulating the time of flow of the heated residuum through the digesting zone to produce a molecular rearrangement of the heated residuum, and producing a fuel oil of lowered viscosity.

55 5. A method of reducing the viscosity of viscous petroleum oil residuum, comprising, subjecting heated viscous petroleum oil residuum, coming from a distillation and fractionation operation, at a temperature of not less than about 700° F., to a pump pressure of about 500 pounds per square inch, sufficient to prevent substantial vaporization thereof, and without further heating passing the heated residuum at said pressure and said temperature through an enlarged digesting zone, regulating the time of flow of the heated residuum through the digesting zone to produce a molecular rearrangement of the heated residuum, and producing a fuel oil of lowered viscosity.

60 6. A method of processing petroleum oils, comprising, separately separating by low pressure distillation and fractionation a lower boiling distillate, a higher boiling distillate, and a viscous petroleum oil residuum from a petroleum oil, at temperatures substantially not less than 700° F., continuously passing the heated petroleum residuum without further heating, and at a temperature of its retained heat from the low pressure distillation operation, through an enlarged digesting zone maintained at an increased pressure of about 500 pounds per square inch, sufficient to prevent substantial vaporization therein, and at a temperature of not less than about 700° F., regulating the time of flow through the digesting zone for about sixty minutes to produce a molecular rearrangement of the heated petroleum residuum, and producing a fuel oil of lowered viscosity.

JOHN C. BLACK.
